UNITED STATES PATENT OFFICE

2,084,053

LEVEL

George W. Wilson, Delbarton, W. Va.

Application April 14, 1936, Serial No. 74,318

1 Claim. (Cl. 33—211)

This invention appertains to new and useful improvements in geometrical instruments, and more particularly to a novel level.

The principal object of the present invention is to provide a level employing a slidable shield which will permit of the level being conveniently used in conventional manner and which when adjusted will cover and protect the fragile part of the level even when the same is roughly handled.

During the course of the following specification other important objects and advantages of the invention will become apparent to the reader.

In the drawing:

15 Figure 1 represents a side elevational view of the level;

Figure 2 represents a perspective view showing how the end blocks and side walls are associated;

20 Figure 3 is a cross-sectional view taken substantially on line 3—3 of Figure 1;

Figure 4 is an end elevational view of the level;

25 Figure 5 is a cross section taken in the plane indicated by the line 5—5 of Figure 1, looking toward the left.

Referring to the drawing wherein like numerals designate like parts, it can be seen that the numeral 5 represents the level stock provided with lateral flanges at its upper and lower longitudinal edges, these flanges being denoted by the numeral 6. The upper and lower flanges are provided with longitudinally extending grooves 7 in their opposed sides for receiving the side walls 8—8 of the shield.

35 At spaced intervals, the stock 5 of the level has openings 9 therein, Figures 1 and 3, in which are mounted the level glasses at 10.

One end of the body 5 is closed as at 11 while 40 its opposite end is open and provided with parallel extensions at 12—12.

The ends of the walls 8—8 are secured by

screws 13 to the end blocks 14 which are notched at their upper and lower ends as at 15, Figures 2 and 4, to accommodate longitudinal central ribs 16 on the upper and lower portions of the stock adjacent to the ends thereof. The said ribs 16 are shown in Figures 1 and 4 on the extensions 12 at the right hand end of Figure 1, and they are also shown in Figure 5 on the upper and lower portions of the stock adjacent to the left hand end thereof.

5 The side walls 8 are provided with open portions 18 and closed or imperforate portions 17. Obviously, by sliding the shield along the body 5, the closed portions 17 can be brought over or opposite the openings 9, thus shielding the 15 level glasses when not in use.

10 By virtue of the side walls 8 of the shield being disposed and slidable in the grooves 7 of the stock flanges 6, the shield is disposed in and protected by the stock.

20 While the foregoing specification sets forth the invention in specific terms, it is to be understood that numerous changes in the shape, size, and materials may be resorted to without departing from the spirit and scope of the invention as 25 claimed hereinafter.

Having described the invention, what is claimed as new is:

20 The level described comprising a stock having transverse openings at intervals in its length and also having upper and lower lateral flanges with longitudinal grooves in their opposed sides, indicating means including glasses in said openings, and a longitudinally slidable shield having side walls disposed in said grooves and also having end portions joining said side walls and guided in the stock; the said side walls of the shield having spaced closed or imperforate portions and also having openings at opposite sides of said closed or imperforate portions.

GEORGE W. WILSON.
